UNITED STATES PATENT OFFICE.

THOMAS L. STINE, OF TREGO, MARYLAND.

PORTABLE BATH-TUB.

1,072,269.

Specification of Letters Patent.

Patented Sept. 2, 1913.

Application filed May 14, 1913. Serial No. 767,650.

To all whom it may concern:

Be it known that I, THOMAS L. STINE, a citizen of the United States, residing at Trego, in the county of Washington and State of Maryland, have invented new and useful Improvements in Portable Bath-Tubs, of which the following is a specification.

This invention is an improved portable bath tub comprising a centrally arranged tub, a funnel-shaped splash guard or apron at the upper side of the tub and extending upwardly and outwardly therefrom, a seat on one side of the apron, a discharge spout for water arranged under the seat and supports connected to the apron and also to the tub and arranged on opposite sides of the seat, as hereinafter described and claimed, the object of the invention being to provide an improved portable bath tub which is cheap and simple, is strong and durable, which provides a comfortable seat for the user and which when not in use may be readily hung up out of the way.

In the accompanying drawing:—Figure 1 is a plan of a portable bath tub constructed in accordance with my invention. Fig. 2 is a vertical central sectional view of the same. Fig. 3 is a detail transverse sectional view 30 on the plane indicated by the line *a—a* of Fig. 1.

In accordance with my invention, I provide a cylindrical tub or basin 1 which may be made of sheet metal or of any other suitable material and is of a suitable size. I also provide a funnel shaped splash guard or apron 2 which may be made integral with the tub or basin and extends upwardly and outwardly from the wall thereof. On one

side of the splash guard or apron is a seat 3, the length of which somewhat exceeds the width of that portion of the apron to which it is attached, so that the inner end of the seat projects a slight distance over the wall 45 of the tub or basin and into the latter, as shown. Opposite the outer end of the seat is a fender or back 4 which is crescent-shaped and is inclined at a greater angle than the apron so that the said fender or back 50 projects upwardly and outwardly from the outer edge of the apron at the outer end of the seat and this fender or back is here indicated as formed separately from the apron and as being made of sheet metal and having its outer edge rolled around a reinforcing wire 5. The outer edge of the apron is

also indicated as rolled around a reinforcing wire 6. The fender or back forms a radial extension of the apron at a point in rear or at the outer end of the seat so as to avoid 60 splashing the floor at that point and also forms a substantial reinforce for that portion of the apron on which the seat is placed and serves to materially strengthen the apron. An outlet spout 7 is also provided 65 for the tub or basin 1, is inclined, arranged under the apron at a point in vertical alignment with the center of the seat, the lower inner end of the said spout extending through the wall of the tub or basin and the 70 outer end thereof being connected as at 8 to the apron. A supporting plate or base 9 of suitable size is arranged under that portion of the apron in which the seat is placed and in line with the bottom of the tub, is connected to the tub by braces 10 and is also connected, at its outer corners to the apron, at points on opposite sides of the seat, by means of a pair of supporting columns or legs 11 which, in practice, may be hollow 75 and may be made of sheet metal and the upper ends of which are provided with flared extensions 12 which are secured directly to the under side of the apron. A ring 13 is attached to the outer edge of the 80 apron at a point diametrically opposite the seat and serves to enable the tub when not in use to be hung up from a nail on the wall or frame or any other support. I also show a soap holder 14 which forms a crescent 85 shape guard wall secured on and extending upwardly from the apron and arranged at a point a convenient distance from one side of the seat.

I claim:—

1. A portable bath tub comprising a centrally arranged tub or basin, a funnel-shaped apron at the upper side thereof and extending upwardly and outwardly therefrom, a seat on one side of the apron and a 100 fender or back projecting outwardly from the apron and connected thereto at a point in rear of the seat, the said fender also forming a reinforce for that portion of the apron on which the seat is located, and supports attached to the apron at a point at opposite sides of the seat to prevent the tub from being overturned when in use.

2. A portable bath tub comprising a centrally arranged tub or basin, a funnel-shaped apron at the upper side thereof and extending upwardly and outwardly there-

from, a seat on one side of the apron and a fender or back projecting outwardly from the apron and connected thereto at a point in rear of the seat, the said fender also forming a reinforce for that portion of the apron on which the seat is located, and supports attached to the apron at a point at opposite sides of the seat to prevent the tub from being overturned when in use, the tub being 10 also provided with a discharge pipe ar-

ranged in an inclined position under the center of the seat and communicating at its inner end with the tub.

In testimony whereof I affix my signature in presence of two witnesses.

THOMAS L. STINE.
